REFRIGERATOR CAR

Arthur A. Helwig, Chicago, Ill., assignor to Standard Railway Refrigerator Company, Chicago, Ill., a corporation of Delaware

Application May 3, 1939, Serial No. 271,428

2 Claims. (Cl. 62—17)

This invention relates to refrigerator cars used to transport perishable commodities at a predetermined temperature. The essential features of a refrigerator car are an insulated body to prevent or retard ingress of heat during warm weather and egress of heat during cold weather and a cooling or heating means depending upon the prevailing outside temperature.

This invention applies particularly to cars in which the cooling means, preferably containers for water ice, eutectic ice, brine or dry ice, are suspended immediately below the ceiling of the car. The lading is supported in spaced relation to the floor by a foraminous rack. Flues, preferably associated with the side walls of the car, communicate between the refrigerant compartment and the space under the floor rack to provide a path for the circulation of air. The path is from the refrigerant compartment downwardly through the aforementioned flues, through the space under the floor rack, and upwardly through the lading compartment to the refrigerant compartment.

An object of the invention is to provide a greater area associated with the refrigerant container. The amount by which air is cooled upon passing over a cold object is dependent upon the extent of the surface of the cold object and upon the velocity of the air movement. Consequently, I provide conduits adapted to be embedded in the refrigerant and having means to direct the circulating air through the conduits, the air being cooled during passage therethrough. The additional surface of the conduits adds to the refrigerating efficiency of the container.

A further object of the invention is to position said conduits so that the temperature thereof is substantially the lowest which may be obtained with the particular refrigerant being used.

It is another object of the invention to utilize the above-mentioned conduits as a reinforcing or stiffening means for the refrigerant container.

Another object of the invention is to provide means to direct a portion of the circulating air through the aforementioned conduits and a portion under the container, thereby permitting some of the air to contact the container bottom which is also usually very cold.

Another object is to provide a substantial space between the conduits and the bottom of the container so that the refrigerant in the container, whether it is solid or liquid, may thoroughly cool the bottom of the container so that the air flowing thereunder may be refrigerated.

Other objects and advantages of my invention

will be apparent from the following detailed description by referring to the accompanying drawing:

Fig. 1 is a partial transverse section of a refrigerator car embodying my invention.

Fig. 2 is a longitudinal section on line 2—2 of Fig. 1.

Fig. 3 is a section on line 3—3 of Fig. 1.

Fig. 4 is a transverse section showing a modified construction.

Fig. 5 is a section on line 5—5 of Fig. 4.

Fig. 6 is a view similar to a portion of Fig. 2 showing a modified construction.

The general parts of the refrigerator car shown are insulated roof 2, side wall 3, floor 4, hatch 5, refrigerant container 6, side wall flue 7, foraminous floor rack 8 and space 9 between rack 8 and floor 4. The refrigerant container 6 is positioned directly below the roof 2 and adjacent the side wall 3. A drip pan 12 is provided below the container 6 and a partition 14 is secured in an upstanding position at the edge of the drip pan 12. The drip pan 12 and partition 14 cooperate with the roof 2 and side wall 3 to form an enclosing structure 11 around the container 6, an air inlet opening 15 being provided by spacing the partition 14 from the roof 2. An air discharge opening 17 which leads to the flue 7 is formed by spacing the drip pan 12 from the wall 3.

Air circulation is as follows: Air in the lading compartment 18 is warmed by contact with the lading and rises to enter the enclosing structure 11 through the air inlet opening 15. The air is cooled by contact with the refrigerant container 6 and falls by reason of its greater density through the discharge opening 17 and flue 7 to the space 9 whence it rises through the rack 8 to the lading compartment 18. Cars of this type usually have a row of refrigerant containers near each wall and directly below the roof so that air flowing from the lading compartment flows between the containers disposed on opposite sides of the car.

In Figs. 1 and 2, the refrigerant container 25 has secured inside thereof a plurality of conduits 26, which conduits extend between the container side 28 adjacent the refrigerator wall 3 and the container side 29 opposite therefrom. The conduits 26 have communication with the exterior of the container through the sides 28, 29 so that air may flow from the inlet opening 15 through 50 the conduits 26 to the discharge opening 17. The conduits 26 are preferably spaced from each other and from the bottom 31 of the container 25 so that the refrigerant in the container may surround the conduits 26 and also be in intimate 55

contact with the bottom 31. The conduits are particularly useful when the refrigerant used is one which melts to a liquid; in this case melted refrigerant is in contact with the entire surface 5 of the conduits 26 and bottom 31, the liquid being retained at a low temperature by contact with the remaining solid refrigerant supported on the upper surfaces of the conduits 26.

As shown in Fig. 1, the container 25 is spaced 10 from the roof 2 to form the passage 35 therebetween and from the wall 3 to form the passage 36. It is intended that a portion of the circulating air flow through the passages 35, 36, as shown by the arrows in Fig. 1. The lower portion 38 of the 15 side 28 embracing the conduits 26 is preferably spaced from the wall 3 a greater distance than the upper portion of the side 28 to provide additional space for the emergence of air from the conduits 26. The container 45 may be arranged 20 as shown in Fig. 4, substantially in contact with the roof 2 and wall 3. In this case, the portion 46 of the side 47 is spaced from refrigerator wall 3 so that air may flow out of the conduits 49.

It may be desirable to associate with the container side 55 remote from the wall 3 a deflector 25 to direct air into the conduits. In Figs. 1 and 3, a deflector 56 is secured near several conduits 26, i. e., the deflector 56 extends uninterrupted adjacent several openings into the conduits 26. 30 The deflector 56 preferably comprises an upstanding portion 57 and a curved portion 59 arranged to guide downflowing air into the conduits. The upstanding portion 57 is preferably spaced from the partition 14 so that a portion of the air may 35 flow through the duct 60 under the container 25.

Deflectors 65 as shown in Figs. 4 and 5 may also be provided. Each deflector 65 is disposed adjacent preferably one conduit 49 although each deflector may be associated with two or more conduits without departing from the spirit of the invention. A deflector 65 preferably comprises a curved lower surface 66 for directing air into the conduits 49 and an upstanding peripheral wall 67 extending substantially around the curved surface 66 with its ends abutting the container side 68. The deflectors 65 are preferably spaced apart to provide openings 69 therebetween for flow of a portion of the circulating air to the duct 70 below the container 45.

It is not intended to limit the invention to conduits of any particular form. Fig. 2 shows the conduits 26 to be circular in cross section while Fig. 6 shows conduits 75 of square cross section. It is to be understood that any shape, such as an

ellipse, may be used without departing from the spirit of the invention.

Fig. 4 shows a modification in which the conduits 49 and bottom of the container 45 are substantially horizontal while in Fig. 1, the conduits 5 26 as well as the bottom of the container 25 are inclined downwardly toward the flue 7 to accelerate the flow of air therethrough.

The accompanying drawing illustrates the preferred form of the invention, though it is to be understood that the invention is not limited to the exact details of construction shown and described, as it is obvious that various modifications thereof, within the scope of the claims, will occur to persons skilled in the art. 15

I claim:

1. In a refrigerator having a refrigerant container below the roof adjacent one of the refrigerator walls, a flue associated with said wall, an enclosing structure for said container having an air discharge opening leading to said flue and an air inlet opening leading from the lading compartment of the refrigerator and means to conduct air through said container in close contact with the refrigerant therein, said means comprising a plurality of conduits extending between the container side adjacent said wall and the container side opposite therefrom and having communication at both ends thereof with the exterior of said container, the upper portion of said adjacent container side being substantially in contact with said refrigerator wall and the portion of said adjacent container side embracing said conduits being spaced from said refrigerator wall. 25

2. In a refrigerator having a refrigerant container spaced below the roof adjacent one of the refrigerator walls, a flue associated with said wall, an enclosing structure for said container having an air discharge opening leading to said flue and an air inlet opening leading from the lading compartment of the refrigerator and means to conduct air through said container in close contact with the refrigerant therein, said means comprising a plurality of conduits extending between the container side adjacent said wall and the container side opposite therefrom and having communication at both ends thereof with the exterior of said container, the upper portion of said adjacent container side being spaced from said refrigerator wall and the portion of said adjacent container side embracing said conduits being spaced from said refrigerator wall a greater distance than said upper portion. 35

ARTHUR A. HELWIG.
